UNITED STATES PATENT OFFICE.

JAMES T. BRACKIN, JR., OF TRENTON, TENNESSEE.

DOOR-LOCK

1,086,136.

Specification of Letters Patent.

Patented Feb. 3, 1914.

Application filed June 27, 1912. Serial No. 706,230.

To all whom it may concern:

Be it known that I, JAMES T. BRACKIN, Jr., a citizen of the United States, residing at Trenton, in the county of Gibson, State 5 of Tennessee, have invented certain new and useful Improvements in Door-Locks; and I do hereby declare the following to be a full, clear, and exact description of the invention, such as will enable others skilled 10 in the art to which it appertains to make and use the same.

This invention relates to improvements in door locks.

The principal object of the invention is to 15 provide a lock of the multiple key type in which the dead-lock latch may be readily shifted to its operative position and locked or retracted as the case may be, and which, when in the former position, will be prevented 20 from being retracted by anyone not knowing the proper combination.

Another object of the invention is to provide 25 a lock of the character described in which the spindle forms part of the combination, and which is adapted under certain conditions to engage the dead-latch and shift the same to its operative position.

A further object of the invention is to 30 provide a lock in which a novel mechanism is arranged to retain the locking pawls and the tumblers out of engagement with the dead-latch when the latter is in its retracted or inoperative position.

A still further object of the invention is 35 to provide a lock of the character described which is provided with a night-latch of novel construction adapted to retain the latch bolt in its operative position.

A still further object of the invention is 40 to provide a lock of the character described which is composed of a relatively few number of parts, is therefore comparatively simple in construction, and is cheap to manufacture.

With these and other objects in view, the 45 invention consists in the construction and novel combination of parts hereinafter fully described, illustrated in the accompanying drawings and pointed out in the claims hereinafter appended; it being understood that various changes in the form, proportion, size 50 and minor details of construction within the scope of the claims may be resorted to without departing from the spirit or sacrificing any of the advantages of the invention.

In the drawings: Figure 1 is a plan view

of a lock constructed in accordance with my invention, the back plate being removed to better disclose the parts, said parts being shown in their operative or locked positions, 60 Fig. 2 is a detail plan view showing the first step employed in retracting the dead-latch, Fig. 3 is a similar view but showing the second step employed in retracting the dead-latch, Fig. 4 is a longitudinal sectional view 65 taken on the line 4-4 of Fig. 1, Fig. 5 is a sectional view taken at right angles to Fig. 4, on a line slightly to the left of the spindle. Fig. 6 is a detail plan view showing the third step employed in retracting the 70 dead-latch, Fig. 7 is a view similar to Fig. 1 but showing the latch bolt in its normal or unlocked position, Fig. 8 is a similar view but showing the first step employed in projecting the dead-latch, Fig. 9 is a detail plan 75 view showing the second step employed in projecting the dead-latch, Fig. 10 is a transverse sectional view showing the third step employed in projecting the dead-latch, Fig. 11 is a perspective view of the pivoted slide, 80 Fig. 12 is a perspective view of the gravity latch, Fig. 13 is a perspective view of the keys employed in conjunction with the lock, and Fig. 14 is a detail side elevation of the spindle lock.

Like reference numerals designate corresponding parts in all the figures of the drawings.

Referring to the drawings, the invention 90 comprises a lock casing, which is designated as a whole by the reference letter A, and this casing includes a front plate 4, a rear plate 5, top and bottom walls 6 and 7 respectively and side walls 8 and 9 respectively. Slidably mounted within an 95 opening 10 formed in the side wall 8 is a dead-latch B, and slidably mounted within an opening 11 arranged in spaced relation to and above the opening 10 is a latch bolt C.

The dead-latch B is formed in its upper 100 edge with spaced front and rear notches 12 and 13, and in the rear end of the lower edge with a notch 14. The rear end of the dead-latch terminates in a centrally disposed flat tail 15 which extends upwardly toward the 105 latch bolt C, and has a sweep 16 formed in its inner edge. Also formed in the tail 5 above the sweep 16 is a slot 17 which is disposed in parallel relation to the dead-latch and receives a bearing pin 18 which is carried by the front plate 4 of the casing A. Carried by the front upper portion of the

tail 15 is a depending pin 19, the inner end thereof being disposed in spaced relation to the back wall 5 of the casing.

The latch bolt C includes the usual shank 5, head 21 and yoke 22, the rear end of the yoke carrying a transverse vertical plate 23. In order to yieldably hold the latch bolt in its projected position, there is provided a coil spring 24 which is disposed between and 10 connected to the yoke 22 and the side wall 9 of the casing. Extending downwardly from the shank 20 of the latch bolt is a lug 25 having a front cam face 26, and projecting upwardly from said shank is a lug 27 having 15 a front cam face 28, the last mentioned lug being disposed in spaced relation to the top wall 6 of the casing.

In order to either project the dead-latch B forwardly to its locking position, or to 20 actuate the latch bolt B, the following mechanism is employed: Formed in the front and back plates 4 and 5 are alined openings 29 and 30 respectively, which register within the yoke 22 of the latch bolt C, and slidably 25 in said openings is a spindle 31. On the outer ends of this spindle are fixed knobs 32 and 33 respectively. Centrally fixed on the spindle is a sleeve 34 which is rotatably mounted within the openings 29 and 30, and 30 which is of a length somewhat greater than the distance between the front and back plates 4 and 5. Disposed around the inner end of the spindle 31 is a helical spring 35, the smaller end thereof bearing against the 35 knob 32 and the larger end bearing against the front plate 4 and having its terminal fixedly connected thereto, said larger end embracing the front end of the sleeve 34. Formed in the sleeve 34 is a transverse slot 40 36, which will be disposed in advance of the front plate 4 when the spindle is in its normal position, as is clearly shown in Figs. 4 and 14 of the drawings. In order to lock the spindle 31 against both axial and longitudinal movements, a latch lever 37 is fulcrumed intermediate its ends, as at 38, upon the front plate 4. One end of this lever is formed with an arcuate recess 39 adapted to fit within the transverse groove 36 above 45 mentioned, and thereby lock the spindle against movement. The other end of the lever terminates in a finger-piece 40, and 50 formed in the outer end of the lever is a depression 41 forming a consequent seat which is adapted to frictionally engage a corresponding projection formed on the front plate 4. It will thus be observed that by 55 means of this projection and seat 41, the lever is held in locking engagement with the 60 sleeve.

Fixed on the sleeve 34 and in advance of the yoke 22 is a cam 42, which is formed with a flat face 43, a base 44 and an apex 45. In the normal or projected position of the latch bolt C, the flat face 43 of the cam is disposed

against the plate 23 of the yoke 22, as is clearly shown in Figs. 1 and 7 of the drawings.

Carried by the spindle 31 is a laterally extending striker arm 46 which is normally 70 disposed in rear of and below the depending pin 19 which is carried by the tail 15 of the dead-latch B. When it is desired to project the dead-latch through the medium of the spindle, said spindle is first shifted 75 longitudinally against the tension of the spring 35 so as to dispose the striker arm 46 behind the pin 19 and in the same plane therewith, whereby upon rotation of said spindle in a right handed direction, said 80 striker arm will engage the pin and thereby transmit a longitudinal movement to the dead-latch, as will be readily understood. In order to assist the forward or projecting movement of the dead latch, a coil spring 47 is connected at one end to the bottom wall 7 of the casing, and at its other end to the latch bolt B. This spring is normally disposed at an inclination so that as the dead-latch is drawn forwardly, said spring 90 will be first compressed and later as soon as the upper end passes the center line the spring will expand and cause the dead-latch to move to its farthest or projected position. 95

In order to lock the latch bolt against retraction, the top wall 6 intermediate the lug 27 and the opening 11 is formed with a longitudinal opening 48. Slidably mounted within this opening is a cam projection 48^a which depends from a finger-piece 49. A flat spring 50 is secured at one end to said top wall, and has its free end extending downwardly for engagement with the projection 48^a. Carried by this spring is a depending stop 51, which is adapted when the latch bolt C is retracted to be positioned in advance of the cam face 28 of the lug 27. In order to position the stop 51 as above described, the finger-piece 49 is shifted longitudinally along the casing, and as a result, the projection 48^a is carried thereby and this projection engages the depending end of the spring 50, causing said spring to be depressed, and as a result, position the stop 105 51 in advance of the cam face 28 as above explained. 110

A pair of locking tumblers 52-52 which are identical in construction, are disposed on opposite sides of the tail 15 of the dead-latch B, and are swingingly mounted at their rear ends upon the bearing pin 18. Each tumbler includes a forwardly extending body portion 53 which terminates at its forward end in a downwardly projecting finger 54 and a forwardly extending hook 55, the finger being adapted to engage within a recess 56 formed in the rear end of the upper face of the dead-latch B, and thereby lock said latch against retraction, as is 120 125 130

clearly shown in Fig. 1 of the drawings. In this position of the tumblers, a fence 57 which is carried by the tail 15 of the dead-latch B co-operates with a usual gating 58 formed on a respective tumbler 52. Depending from the rear end of each tumbler is a forwardly extending cam finger 59 which, when the tumbler is in the position as shown in Fig. 1, is disposed across the sweep 16 of the dead-latch B. Centrally secured to the front face 4 is a post 60, which is formed with a threaded opening 61 for receiving a screw (not shown), said screw being employed for securing the front 15 and back plates 4 and 5 together. A flat spring 62 has its rear end fixedly secured to the body portions 53 of the tumblers 52, and the forward or free end of this spring bears against the post 60 and tends to yieldably urge said tumblers downward for engagement with the dead-latch B.

Secured to the front plate 4 of the casing intermediate the dead-latch B and latch bolt C and slightly in advance of the lug 25, 25 is a pivot pin 63. Also secured to the front plate 4 intermediate the pin 63 and the tumblers 52 is a pivot pin 64, and formed in said plate intermediate the pins 63 and 64 is a key-hole 65. A gravity pawl 66 is fulcrumed adjacent one end upon the pin 63, and this pawl normally rests upon the upper edge of the dead-latch B, and is adapted to engage within the notch 12 thereof when said latch is disposed in its projected position, as is clearly shown in Fig. 1 of the drawings. In order to centrally support the pawl 66 between the front and back plates 4 and 5, there is provided a swinging weight 67 which is pivotally mounted upon the pin 40 63, and which is longitudinally slotted to receive said pawl. The upper end of this pawl terminates beyond the pin 63 in a catch 68. A second gravity pawl 69 is fulcrumed intermediate its ends upon the pin 64, and a 45 swinging weight 70, similar in construction to the weight 67, is also swingingly mounted upon the pin 64 for engagement with the pawl 69. The upper end of this pawl terminates above the pin 64 in a catch 71. The 50 pawl 69 is adapted when the dead-latch B is disposed in its projected position to engage within the recess 13, as is clearly shown in Fig. 1 of the drawings.

In order to lock the pawls 66 and 69 out 55 of engagement with the dead-latch B, the front plate 4 carries a bearing pin 72, and fulcrumed upon this pin is a gravity latch 73, said pin being disposed intermediate the pawl 69 and the tumbler 52. The free end 60 of the latch is formed with a depending hook 74 and with an upwardly projecting head 75. Centrally formed on the lower face of the latch is a second hook 76, the depth of this hook being somewhat greater 65 than the depth of the hook 74 for a reason

which will hereinafter appear. Depending from the pivot end of the latch is a spaced pair of ears 77—77, and fulcrumed upon a transverse pin 78 which connects said ears is a vertically swinging trip 79, the front 70 end of said trip being formed with an upwardly extending stop 80, and the rear end of said trip being formed with a cam face 81. It will thus be observed that this trip is normally held in a horizontal position, with 75 the stop 80 abutting the latch 73, and also that the cam face 81 is disposed in the path of movement of the projections 55 of the tumblers 52.

Formed in the front plate 4 below the tail 15 of the dead latch B is a key-hole 82. Secured to said front plate 4 between the key-hole 82 and the side wall 9 is a bearing pin 83. A pivoted slide is designated as a whole by the reference numeral 84, and this slide 85 includes a head 85 and a tail 86. Extending forwardly from the tail 86 are longitudinal guide pins 87—87, the forward ends thereof projecting in suitable openings (not shown) formed in the rear portion of the head 85. Coil springs 88 are disposed around the respective pins 87 intermediate the head 85 and tail 86 and serve to yieldably retain said head and tail in spaced relation. The forward end of the head 85 is recessed, as at 89, to form a seat, said seat being divided by a transverse web 90. When the head 85 is in its normal position, the web 90 projects slightly into the key-hole slot 82. The tail 86 is formed with a longitudinal slot 91, which receives the bearing pin 83 and thereby permits of a sliding as well as pivotal movement of said slide. The rear end of the tail 86 terminates in a rearwardly and upwardly inclined finger 92. 100

Fulcrumed upon the pin 93 carried by the front plate 4 and disposed between the tail 86 and the wall 9, is a spring latch 94, one end 95 thereof being yieldably held in engagement with the finger 92 by means of a 105 coil spring 96. The other end of this latch is formed with a hook 97.

Carried by the front plate 4 in rear of the key-hole 82 and slightly below the same is a bearing pin 98, and fulcrumed intermediate its ends upon this pin is a locking lever 99, the forward portion thereof being formed with an upwardly extending cam projection 100 which is disposed slightly in advance of the key-hole opening 82. The forward end of this lever terminates in an upwardly extending finger 101 which is adapted to engage within a recess 102 formed in the rear portion of the lower face of the dead-latch B when said latch is in its projected position. The rear end of this lever terminates in an upwardly extending catch 103 which is adapted to be engaged by the hook 97, as will hereinafter more fully appear. In order to centrally secure the lever 99 intermediate 115

125

130

diate the front and back plates 4 and 5, there is provided a spacing ring 104 which is pivotally mounted upon the pin 98, and is longitudinally slotted to receive said lever. A flat spring 105 is secured at its forward end to the bottom wall 7 of the casing A and the forward or free end of this spring is formed with a transverse head 106 which bears against the lever 100 in advance of the pin 98 and tends to yieldably urge the forward end of the lever upwardly.

Extending upwardly from the tail 86 of the pivoted slide 84 is a post 107, and this post is connected to one end of a coil spring 108, the other end of said spring being fixedly connected to the yoke 22 of the latch bolt C, said spring being trained around a pulley 109 which is mounted upon a pin 110 carried by the front plate 4 of the casing. The spring 108 tends to normally hold the head 85 of the pivoted slide 84 in its normal position, as shown in Fig. 1 of the drawings.

My invention further comprises a pair of keys D and E which are respectively adapted to be inserted through the key holes 65 and 82. The key D includes the usual shank 111 and ward 112. The key E includes a shank 113, a reduced end 114, a ward 115 and a pilot end 116 which is pointed, as at 117. The reduced end 113 is centrally cut away, as at 118, for engagement with the web 90 of the head 85 of the pivoted slide 84. The ends of the shanks 111 and 113 opposite the wards 112 and 115 are pivotally connected by a pin 119, and connected to this pin is a clevis 120 by means of which the keys D and E may be readily attached to a key-ring or the like (not shown). The inner face of the shank 113 is recessed, as at 121, to receive the free edge of the ward 112 when said keys are folded, as will be readily understood.

In operation, assuming that the parts are in their operative or locked positions as shown in Fig. 1 of the drawings, the following steps are necessary in order to retract the dead-latch B. The spindle 31 is rotated in a right handed direction by means of either of the knobs 32 or 33. As a result, the apex 45 of the cam 52 is caused to bear against the plate 23 and thereby retract the latch bolt 21 against the tension of the spring 24, the movement of said latch bolt drawing the cam lug 25 rearwardly from its engagement with the head 75 of the gravity latch 73, as is clearly shown in Fig. 2 of the drawings. The ward 112 of the key D is then inserted through the key hole 65. This key is then rotated in one direction so that the ward 112 will engage the cam projection 71 of the pawl 69 and swing said pawl upon its pivot 64, thus disengaging said pawl from the recess 13 of the dead-latch B. As a result, the pawl 69 will be retained in its disengaged position by means 65 of the hook 76 which is formed on the grav-

ity latch 73, as is clearly shown in Fig. 2. The key D is then turned in the opposite direction so that its ward 112 will engage the pawl 66, and as a result, raise said pawl from its engagement with the recess 12 of the dead-latch B. As the pawl 66 is thus shifted to its inoperative position, the catch 68 thereof will ride under the hook 74 of the gravity latch 73. It will be observed in this connection that by means of the hook 76 of the gravity latch being deeper than the hook 74, the pawl 66 may be swung to its disengaged position without releasing the pawl 69. It will thus be observed that the pawls 66 and 69 are held out of engagement with the dead-latch B by means of the gravity latch 73. The spindle 31 is then returned to its normal position, and, as a result, the spring 24 will return the latch bolt 21 to its normal position. In this position of the bolt 21, the cam lug 25 will be disposed against the head 75 of the gravity latch 73 and hold the latch against upward swinging movement. It will thus be observed that the latch bolt 21 serves as a lock to prevent the gravity latch 73 from movement, and as a result, the pawls 66 and 69 are positively locked in their inoperative positions. The key D is then withdrawn and the ward 115 of the key E is inserted through the key hole 82. As the key is thus inserted, the pilot end 116 thereof will abut the web 90 of the head 85 of the pivoted slot 84, and as a result, shift said slide toward the end wall 9 of the casing A, as is clearly shown in Fig. 6 of the drawings. In this position of the slide 84, the springs 87 will be compressed, thereby allowing the head 85 to shift toward the tail 86. The tail 86 moves toward the wall 9 by reason of the slot 91, as will be readily understood. As the slide 84 thus moves, the finger 92 thereof bears against the end 95 of the spring 94. As a result, the hook 97 is moved outwardly from the wall 9 toward the catch 103 of the locking lever 99. The key E is then turned so that the ward 115 will engage the cam 100 of the locking lever 99, and as a result, rock said lever so as to disengage the finger 101 thereof from 115 engagement with the recess 102 of the dead-latch B. As the lever 99 is thus rocked upon its pivot 98, the springs 87 of the slide 84 will cause the tail 86 to exert a yieldable pressure upon the end 95 of the latch 94, 120 and as a result, automatically cause the hook 97 of said latch to engage the catch 103 of said locking lever 99. It will thus be observed that the finger 101 is held by means of the latch 94 out of engagement with the 125 dead-latch B. Upon further rotation of the key E in the same direction, the ward 115 will bear against the cam fingers 52 of the tumblers 52 and raise the forward ends 53 of said tumblers. As the tumblers are 130

thus raised, the hooks 55 thereof will be caused to engage against the cam face 81 of the gravity trip 79 and swing said trip upwardly upon its pivots 78, said tumblers 5 being moved upwardly against the tension of the flat spring 62. As soon as the projections 55 of the tumblers are disposed above the trip 79, said trip will by gravity return to its normal position. As soon as the ward 10 115 of the key E leaves the tumblers, said tumblers will be held above the dead-latch B by means of the projections 55 engaging the trip 79. Thus it will be observed that the fingers 54 of said tumblers are held out 15 of engagement with the recess 56 of said dead-latch. As the key E is further rotated in the same direction, the ward 115 will engage the sweep 16 of said dead-latch and retract said latch, as will be readily 20 understood.

In order to automatically return the locking lever 99 to its normal position against the dead-latch B so that the finger 101 thereof will engage within the recess 102 when said latch is projected, the spindle 31 is rotated toward the right, and as a result, the point 45 of the cam 42 will bear against the plate 23 and cause the latch bolt C to be retracted against the tension of the spring 25 108. As the latch bolt thus moves, the spring 108 is compressed, and this spring which is trained around the roller 109 tends to hold the post 107 and consequently the pivoted slide 84 in a fixed position, as is clearly 30 shown in Fig. 6 of the drawings. The key E is then further rotated, and as a result, the ward 115 will engage the head 85 of the slide 84 and cause said slide to swing upon its pivot pin 83, as shown by the dotted lines 35 in Fig. 6 of the drawings. This movement of the slide 84 withdraws the finger 92 from the end 95 of the spring latch 94. The spring 96 then draws the hook 97 of said latch out from engagement with the catch 40 103 of the locking lever 99. As a result, the spring 105 which bears against the forward end of said locking lever 99 causes the lever to swing upon its pivot 98 so that the finger 101 will bear against the dead latch B. As 45 soon as the ward 115 of the key E is turned to register with the key hole 82, the pivoted slide 84 will return to its normal or horizontal position by means of the spring 108. The spindle 31 is then rotated to its normal 50 position and the parts of the lock will be in the positions as shown in Fig. 7 of the drawings. The spindle 31 is then rotated in the opposite direction, this movement causing the base 44 to bear against the plate 23 and 55 retract the latch bolt C. As a result, the cam lug 25 will be disengaged from the head 75 of the gravity latch 78, and as a result, the spring 62 will through the medium of the tumbler 52 and trip 79, swing the gravity

latch upwardly so as to disengage the pawls 65 66 and 69, thereby permitting said pawls to drop upon the dead latch B, as clearly shown in Fig. 8 of the drawings.

What is claimed is:

1. A door lock comprising in combination, 70 a dead latch, a spindle, and means carried by the spindle normally disposed out of engagement with the dead latch adapted in one position of said spindle to project the said latch upon rotation of the spindle in 75 one direction.

2. A door lock comprising in combination, 79 a dead latch, a spindle and means carried by the spindle normally disposed out of engagement with the dead latch and adapted 80 in one position of said spindle to engage directly with said latch to project the latter upon rotation of the spindle in one direction.

3. A door lock comprising in combination, 85 a dead latch, a pin extending laterally therefrom, said pin being rigid with the latch, a spindle and a striker arm extended laterally from the spindle, said arm being extended through the spindle and disposed normally out of engagement with the pin 90 and adapted in one position of said spindle to engage with said pin to project the latch upon a partial rotation of the spindle in one direction.

4. A door lock including in combination, 95 a dead latch having a recess formed therein, a key-actuated gravity pawl adapted for engagement within the recess when the latch is in its projected position, and a gravity latch engageable with the pawl for retaining 100 the same against movement.

5. A door lock including in combination, 105 a dead latch having a recess formed therein, a key actuated gravity pawl adapted for engagement within the recess when the latch is 110 in its projected position, a gravity latch engageable with the pawl for retaining the same against movement, and an element normally engaging the gravity latch to lock the same against movement.

6. A door lock including in combination, 115 a dead latch having a recess formed therein, a key actuated gravity pawl adapted for engagement within the recess when the latch is in its projected position, a gravity latch engageable with the pawl for retaining the same against movement, an element normally engaging the gravity latch to lock the same against movement, and means for withdrawing the element from engagement 120 with said gravity latch.

7. A door lock including in combination, a dead latch having a recess formed therein, a key actuated gravity pawl adapted for engagement within the recess when the latch 125 is in its projected position, a gravity latch engageable with the pawl for retaining the same against movement, a latch bolt having

- a projection engageable with the gravity latch to lock the same against movement, and means for actuating said bolt to disengage the projection from said gravity latch.
5. 8. A door lock including in combination, a dead latch having a recess formed therein, a key actuated gravity pawl adapted for engagement within the recess when the latch is in its projected position, a gravity latch engageable with the pawl for retaining the same out of engagement with the dead latch, an element normally engaging the gravity latch to lock the same against movement, a trip pivoted to the gravity latch, a pivoted key-actuated tumbler normally engaged with the dead latch and adapted in its inoperative position to be supported by said trip, and means for withdrawing the element from engagement with
- 10 said gravity latch for simultaneously releasing said pawl and tumbler.
9. A door lock including in combination, a dead latch having a recess formed therein, a key actuated gravity pawl adapted for engagement within the recess when the latch is in its projected position, a gravity latch engageable with the pawl for retaining the same out of engagement with the dead latch, an element normally engaging the gravity latch to lock the same against movement, a trip pivoted to the gravity latch, a pivoted key-actuated tumbler normally engaged with the dead latch and adapted in its inoperative position to be supported by said trip, means for withdrawing the element from engagement with said gravity latch, and a spring engageable with the tumbler for returning the same to its initial position and simultaneously releasing the gravity latch
- 15 from its engagement with the pawl.
10. A door lock comprising in combination, a dead latch, a spring pressed locking lever engageable with the latch when the latter is in its projected position, said lever being formed with a cam adapted to be engaged by a key for retracting the lever from its engagement with the latch, and a
- key-actuated means for locking said lever in its inoperative position.
11. A door lock comprising in combination, a dead latch, a spring pressed locking lever engageable with the latch when the latter is in its projected position, said lever being formed with a cam adapted to be engaged by a key for retracting the lever from its engagement with the latch, a spring actuated latch normally disposed out of engagement with said lever, and an element arranged to be actuated by the key to swing the latch to engage the lever when the latter is in its inoperative position.
12. A door lock comprising in combination, a dead latch, a longitudinally movable and axially rotatable spindle, a coiled spring engaged on the spindle to yieldingly retain the same in its normal position against longitudinal movement and means carried by the spindle normally disposed out of engagement with the latch and adapted when the spindle is moved longitudinally against the tension of the spring to directly engage with said latch for shifting the same.
13. A door lock comprising in combination, a dead latch having an integral tail piece, a pin extending laterally from the upper end thereof, a longitudinally movable and axially rotatable spindle, means exteriorly acting on the spindle for yieldingly retaining the same against longitudinal movement and shifted in one direction and a striker arm extending laterally from the spindle and normally disposed out of alignment with the pin, whereby when the spindle is shifted to its opposite limit against the action of the resilient means and rotated, said arm will engage the pin to partially project the latch.
- In testimony whereof, I affix my signature, in presence of two witnesses.
- JIM. T. BRACKIN, Jr.
- Witnesses:
- T. K. HAPPEL,
J. B. COPELAD.
